UNITED STATES PATENT OFFICE.

CARL SIGFRED CASPERSON, OF NEW BRITAIN, CONNECTICUT.

COMBINATION DRAWBOLT AND LOCK.

1,410,995.

Specification of Letters Patent. Patented Mar. 28, 1922.

Application filed September 7, 1921. Serial No. 499,094.

To all whom it may concern:

Be it known that I, CARL S. CASPERSON, a citizen of the United States, residing at New Britain, in the county of Hartford, and 5 State of Connecticut, have invented a new and useful Combination Drawbolt and Lock, of which the following is a specification.

The present invention relates to improvements in locks, and is more particularly directed to that type of lock adapted to be used on suit cases and wardrobe trunks.

The object of the invention is to provide a locking device in cooperative relation with 15 a complementary means for preventing opening of the trunk or any closure to which the device may be applied, the complementary means being further adapted to automatically draw the usual top and bottom plates 20 of the lock together as the lock casing is forced into place.

The invention will be best understood from a consideration of the following detailed description taken in connection with 25 the accompanying drawing forming part of this specification, with the understanding, however, that the invention is not confined to any strict conformity with the showing in the drawing, but may be changed 30 and modified so long as such changes and modifications mark no material departure from the salient features of the invention as expressed in the appended claims.

In the drawing:

35 Fig. 1 is a view in perspective of my improved lock applied to the trunk.

Fig. 2 is a view in perspective of the lock in open position with the top of the trunk spaced from the body of the trunk.

40 Fig. 3 is a vertical section taken along the line 3—3 of Fig. 1 of the lock in closed position.

Fig. 4 is a vertical section of the lock shown in Fig. 1 in open position.

45 Fig. 5 is a transverse section of the lock taken along the line 5—5 of Fig. 1.

Fig. 6 is a front view of a modified form of the lock.

50 Fig. 7 is a view of the same in open position and partly in section.

Fig. 8 is a vertical section of the lock taken along the line 8—8 of Fig. 6.

Fig. 9 is a plan view of a modified form of the latch bolt.

55 Referring to the drawing, 1 and 2 represent the respective hinged sections of an

ordinary wardrobe trunk, their abutting or meeting edges being indicated by the line 3, shown in Figs. 1 and 6.

The top or strike plate 4, having a depressed or offset portion 5, is spaced from the trunk cover 1 by means of the base plate 6, and the top plate and base plate 6 are secured to the top of the trunk 1 by means of rivets 7. A box-shaped strike or keeper 8 is struck from a piece of metal, (or drawn from the plate 4) with its side and rear walls bent inwardly at right angles to the body of the keeper, and secured to the top plate 4 by means of lugs 9 projecting through slots 10 in the top plate 4. The bottom of the keeper is open. Depending from the bottom edge of the top plate 4 is a tongue 10 provided with a narrow flange 11 projecting forwardly from said tongue, the ends of said flange being rounded.

A bottom plate 12 is secured to the lower half or body section of the trunk by rivets 13 and is provided with an outwardly projecting box-like bracket 14 secured by means of lugs 15 projecting through slots in the bottom plate 12 and bent over to embrace the rear of said bottom plate. The bracket 14, like the keeper or strike 8, is formed of one piece of metal, and may be formed integral with said plate.

Pivoted at 16 within the bracket is a lock casing 17 having a draw bar 18 at its lower end adapted to cooperate with the flange 11. When the lock casing 17 is shoved inwardly towards the top plate 4 so that the latch bolt 19 will be engaged by the strike or keeper 8, the two sections of the trunk will be drawn together by reason of the draw bar 18 engaging and pressing downwardly upon the flange 11, as shown in Fig. 3.

The latch bolt 19 forms part of the mechanism of the lock 20 which is secured within the lock casing 17 by means of the inturned lugs 21 embracing the rear portion of said lock. The lock 20 comprises a barrel 22 projecting slightly beyond the outer edge of the lock casing 17 and is provided with the usual slot 23 adapted to receive a key for withdrawing the latch bolt 19 from the keeper or strike 8. The interior formation of the slot 23 of the barrel 22 may be of any improved configuration which is ordinarily used in standard locks. A spring 24 mounted in the lock 20 engages a lug 25 on the latch bolt 19 to maintain the latch bolt outwardly from the lock 20 in order that the

latch will always be in a position to engage the strike 8. The inner side of the projecting portion of the latch bolt 19 is beveled so that as the lock casing is moved upon its hinge pin 16 and forced against the top section 1 of the trunk, the rounded portion of the latch bolt will cause the latch bolt 19 to be depressed until it is forced sufficiently downwardly to slip beyond and into the keeper 8.

If will be seen that as the lock casing 17 is moved inwardly upon its hinge pin 16, the draw bar 18 will engage the flange 11 and force the top plate and likewise the cover 1 of the trunk downwardly, or in other words draw the two sections together, so that the latch bolt 19 will engage the keeper 8 and be forced beneath and to the rear of said keeper to lock the two sections together. Furthermore, the rounded outer edge 26 of the strike or keeper 8 will be engaged by the inner edge of the top 27 of the lock casing 17, and further assist in drawing the two sections of the trunk together in order that the latch bolt 19 may snap to the rear of the strike 8.

Figs. 6 to 9, inclusive, illustrate a modification of the device shown in Figs. 1 to 5. To the top plate 4, which is identical in construction with the top plate shown in Figs. 1 to 5, is secured the strike or keeper 8 and the depending tongue 28 provided with a flange 29. Upon both sides of the tongue 28 are integrally formed shoulders 30, the purpose of which will be described later. The lock casing 31 is pivoted on a hinge pin 32 passing through perforated ears 33 of a bracket 34, which is mounted on the bottom plate 12. The shoulders 30 are adapted to abut the ears 33 of the bracket 34 when the two sections of the trunk are locked together.

A latch bolt 35, shown in detail in Fig. 9, is slidably mounted within the lock casing 31, and is formed of sheet metal bent upon itself and having a spaced portion or loop 36, through which is inserted a bar 37 having the finger pieces 38 projecting through slots formed in the sides of the lock casing 31. The lower end of the latch bolt has a stud 39, which is surrounded by a spring 40, the upper end of which engages the shoulder 41 on the latch bolt, while the lower end of the spring rests in engagement with the lower portion of the lock casing, so that the spring will always tend to force the latch bolt 35 upwardly, in order that it will engage the strike or keeper 8 on the top plate 4, when the lock casing is moved into closed position.

A lock barrel 42, which is provided with the usual slot 43 for the insertion of a key, is rotatably mounted in the latch bolt 35. A lock arm 44 is rotatably mounted upon the barrel 42 and moves therewith. When a key is inserted in the slot 43, it will be

adapted to rotate the barrel and the lock arm 44 simultaneously. The lock arm 44 is provided with a rearwardly projecting portion 45 adapted to ride upon the outer surface of the latch bolt 35 and engage indentations 46 in the latch bolt 35 in order to hold the lock arm 44 in certain predetermined positions. The lock arm 44 engages an inward lug 47 on the lock casing 31 and prevents movement of the latch bolt 35, when the same has been locked by a key.

The locking position of the lock arm 44 is shown in dotted lines in Fig. 9, and in full lines in Figs. 8 and 9. When the lock arm is placed in inoperative position, as shown in Fig. 9, the latch bolt may be operated freely by means of the finger pieces 38, projecting slightly beyond the lock casing 31, against the tension of the spring 40.

The flange 29 is adapted to be engaged by a draw bar 48 of the lock casing 31 when the lock casing is shoved inwardly into locking position with the strike or keeper 8 so that this draw bar 48, as it engages the draw flange 29, will force the two sections of the trunk together.

As has been explained with reference to Figs. 1 to 5, the upper rounded portion 26 of the strike 8 is adapted to be engaged by the top 49 of the lock casing 31 and likewise assist in drawing the two sections together.

One of the novel features of this invention is the provision of the depending tongue for the top plate having outstanding flange at the lower end thereof. These elements are marked 10 and 11, respectively, in Fig. 2, and 28 and 29, respectively, in Fig. 7. This tongue with its flange constitutes what is known in mechanics as a dowel. In this instance, however, it not only functions as a dowel, but constitutes a lock, as the flange 11 engages beneath the bar 18 of the lock casing in the first form of the invention, while the flange 29 engages with the bar 48 of the lock casing in the second form of the invention, and is locked in its engagement by the latch bolt in both forms of the invention.

So far as I am aware, it is new in suitcase and trunk locks to provide for the double locking of the trunk in the manner herein shown and described.

Referring to the form shown in Figs. 1 to 5, the lock casing 17 with its latch bolt 19 engages a keeper 8, while the draw bar 18 of the lock casing is engaged by the flange 11 of the tongue 10. In the other form of the invention shown in Figs. 6 to 9, inclusive, the latch bolt 35 engages with the keeper 8 and forms one lock, while the draw bar 48 of the lock casing 31 is engaged by the flange 29 of the tongue 28 and constitutes the other lock.

It is further noted that the lock casing 17 or 31 in both forms of the invention em-

braces the sides and top of the keeper 8 in addition to which the latch bolt fits within the keeper.

In the form shown in Figs. 1 to 5, inclusive, a box-like bracket 14 gives lateral support to the lock casing 11, in addition to which the keeper 8 fitting within the lock casing adds to the lateral support of the latter. In this manner, the locking of the trunk is made very rigid, and there are no projecting parts which would be apt to be torn off by rough usage.

What I claim is:—

1. In a lock, a top plate provided with a keeper and a depending flange, a bottom plate, a lock casing provided with a latch bolt, pivoted on the bottom plate and cooperating with the keeper to prevent relative movement between the top plate and bottom plate, the bottom of the lock casing engaging the flange to further resist movement between the top plate and bottom plate.

2. In a lock, a strike plate provided with a flange, a bottom plate provided with a draw bar adapted to engage the flange to prevent relative movement of the top plate and bottom plate, and means to prevent disengagement of the draw bar and flange.

3. In a lock, a strike plate, a bottom plate, means on the strike plate engaging means on the bottom plate to prevent relative movement of the two plates, and means for locking the two means in immovable position.

4. In a lock, a strike plate provided with a keeper, and a depending member, a flange projecting outwardly from the depending member, a bottom plate, a lock casing provided with a spring-pressed latch bolt cooperating with the keeper to hold the lock casing in position against the strike plate, and means on the lock casing engaging the flange to prevent relative movement between the strike plate and the bottom plate.

5. In a lock, a strike plate provided with a keeper and a depending member, a bottom plate, a lock casing pivoted on the bottom plate and provided with means engaging the keeper on the strike plate, the depending member being adapted to be projected between the lock casing and the bottom plate and provided with means for engaging the lock casing to prevent relative movement of the two plates when said lock casing is locked to the strike plate.

6. In a lock, a strike plate provided with a keeper and a flange, a bottom plate, a lock casing provided with a spring-pressed latch bolt and pivoted on the bottom plate, said bolt cooperating with the keeper to prevent relative movement between the strike plate and bottom plate, the bottom of the lock casing engaging the flange to further resist movement between the strike plate and bottom plate, and the top of the lock casing

engaging the keeper to resist relative movement between the strike and bottom plates. 65

7. In a lock, a top plate provided with a keeper, and a depending tongue, a flange projecting outwardly from the tongue, a bottom plate, a lock casing pivoted on the bottom plate and provided with a spring-pressed latch bolt cooperating with the keeper to hold the lock casing in position against the strike plate, and means on the lock casing engaging the flange when the lock casing is moved inwardly towards the top plate to draw the top plate into engagement with the bottom plate. 70 75

8. In a lock, a strike plate, a bottom plate, means pivoted on the bottom plate and adapted to engage a rigid means on the top plate to draw the two plates together, and means on the pivoted means and engaging the strike plate to lock the plate in position. 80 85

9. In a lock, a bottom plate and a top plate movable relative to the bottom plate, a lock casing hingedly mounted on the bottom plate, a tongue depending from the top plate, a flange rigidly mounted on the tongue and adapted to be located between the hingedly mounted lock casing and the bottom plate, the lock casing being adapted to engage the flange when the lock casing is moved on its hinged mounting to draw the top and bottom plates together. 90 95

10. In a lock, a bottom plate and a top or strike plate movable relative to the bottom plate, a lock casing adapted to have locking engagement with the top plate, and provided with a draw bar adapted to engage a flange on the strike plate and force the bottom and top plates into engagement when the lock casing is forced into locking engagement with the top plate. 100 105

11. In a lock, the combination of a top plate provided with a depending tongue having an outstanding flange, of a bottom plate, a lock casing pivoted to the bottom plate, a keeper on the top plate, a latch bolt in the lock casing engaged with said keeper, and means on the lock casing to engage the flange on said tongue whereby a double lock is provided. 110

12. In a lock, the combination of a top plate provided with a keeper and a depending tongue having a projecting locking flange, a bottom plate having a pivoted lock casing to engage with the flange of said tongue, and locking means provided in the lock casing to engage with the keeper of the top plate, thereby forming a double lock. 115 120

13. In a lock, the combination of a top plate provided with a depending tongue having a locking flange, a bottom plate having a box-like bracket provided thereon, a lock casing pivoted to and within the

bracket and carrying a latch bolt and having a draw bar, and a keeper on the top plate, whereby when the lock casing is swung inwardly the draw bar is engaged 5 with said flange and the latch bolt is engaged with said keeper, thereby forming a double lock.

14. In a lock, the combination of a top plate having a box-like keeper with its 10 lower end open, a bottom plate, a lock casing pivoted to the bottom plate and having a latch bolt to project within the opening of the keeper, said lock casing having its top and sides spaced from the latch bolt 15 and adapted to surround the sides and top of the keeper.

15. In a lock, the combination of a top

plate having a box-like keeper projecting therefrom with its lower end open, a bottom plate, a rectangular lock casing pivoted to the bottom plate and having a latch bolt within the same adapted to be projected within the opening of the keeper and engage the same, said lock casing having its top and sides spaced from the latch bolt 25 and adapted to surround the sides and top of the keeper, the top of the lock casing being adapted to engage with the top wall of the keeper.

In testimony, that I claim the foregoing 30 as my own, I have hereto affixed my signature.

CARL SIGFRED CASPERSON.
